7 Claims. (Cl. 307—88.5)

This invention relates to electronic circuits, particularly to pulse shaping in such circuits.

In some practical applications of pulse circuitry, relatively high energy pulses of microsecond duration and extremely fast rise and fall times are required. A typical example is pulsing the control grid of traveling wave tubes for beam interruption purposes. Here, pulses in the range of 300 to 500 volts drawing quarter and half ampere or higher currents are frequently required.

Heretofore, in the design of such circuits, if high driving currents were applied to a transistor switch in order to produce fast rising pulses, the large transistor storage times caused by hard driving have resulted in long trailing edges on the output pulse. Vacuum tube pulse shaping circuits avoid this storage problem; but, in addition to space and heat dissipation difficulties, they are relatively slow and have a comparatively high internal impedance at high power levels. Also, low output impedance during the fall time of the pulse and immediately after pulse occurrence has been practically unattainable at the energy levels desired.

Accordingly, a primary object of the present invention is to provide a practical means for producing short fall times on high energy pulses generated from a transistor switch which is overdriven to obtain faster rise times.

Other objects of the invention are to provide, in a high power pulse generator: means for maintaining a low output impedance during the fall time of the pulse and immediately after pulse occurrence; a high speed trailing edge clamp; a pulse trailing edge clamp with a minimum space requirement; a pulse trailing edge clamp with low input power requirements; and, an improved pulse shaping circuit.

These and related objects are accomplished, in one illustrative embodiment of the invention, by a pulse generator which includes: a clock; a driver amplifier; a trigger amplifier; a transistor switching circuit; and, a pulse trailing edge clamp.

The clock supplies square shaped pulses to both the driver amplifier and the trigger amplifier. The driver amplifier supplies a relatively low voltage, high current, square wave signal input to the transistor switching circuit which includes a variable resistor, a pair of transistors and a pair of direct current supplies serially connected across the individual transistors and the primary of a pulse transformer. The circuit is so arranged that one transistor is direct current driven and the other is pulse driven. With the circuit in "off" condition the direct current driven transistor is biased by leakage currents from collector to emitter to maintain stability. Also, the total supply voltage is divided across the transistor chain so that the breakdown voltage of each individual transistor is not exceeded. In order to obtain an output pulse across the secondary of the transformer, the relatively high current square wave signal is applied to the base of the pulse driven transistor to turn it on quickly. This allows forward biasing of this transistor so that ground potential is effectively moved to the transistor side of the transformer. As a result, almost the total supply voltage drop occurs across the transformer primary. After pulse occurrence, the pulse driven base is returned to the reverse bias direction and both transistors turn off. The voltage level of the output pulse is controlled by the variable resistor.

2

The trigger amplifier supplies a trigger pulse to the trailing edge clamp circuit which consists of a gated diode connected across a tertiary winding of the output pulse transformer. One terminal of the trigger amplifier, the cathode of the gated diode and one terminal of the tertiary winding are all connected to a common ground. The function of the trigger amplifier is to produce a pulse of sufficient energy to fire the gated diode at the trailing edge of the square wave pulse from the pulse generator. As soon as the diode is fired, the tertiary winding is shunted by less than one ohm impedance and the energy which is stored in the transformer is dissipated. Hence, any storage effects of the transistor switch due to hard driving are clamped out and the pulse transformer output impedance is reduced to substantially zero until all energy sources are either removed or depleted. As a result, the fall time of the pulse across the transformer secondary is determined by the trigger location and the output impedance will approximate zero during fall time and immediately following pulse occurrence.

Other objects and features of the invention will be apparent from the following description, reference being had to the accompanying drawing, the single figure of which is a schematic circuit diagram of a pulse generator embodying the invention.

Referring to the drawing, the invention is illustrated as embodied in a pulse generator including: a clock 10 having its output connected to both a driver amplifier 11 and a trigger amplifier 12. The clock may be a triggered 30 monostable flip-flop with a pulse width control. The driver amplifier may be transformer coupled to the clock generator for isolation and consist of successive emitter follower stages to provide power gain with low output impedance; and, the trigger amplifier may be a differentiator 35 delay in combination with cascaded emitter followers to provide gain and control output impedance.

The driver amplifier 11 supplies the input signal to the specialized transistor switching circuit by means of a negative output terminal which is connected to the negative 40 side of a direct current supply 13 and a positive output terminal which is connected, through a coupling capacitor 14, to the base of a transistor 15. Hence, transistor 15 is pulse driven. The transistor switch also includes a variable resistor 16, an additional transistor 17, and another direct current supply 18. Supplies 13 and 18 are serially connected across the primary winding 19 of the output pulse transformer.

The collector of transistor 17 is connected through primary 19 to the positive terminal of the direct current supply 13. The negative terminal of supply 13 is, in turn, connected to the positive terminal of supply 18 and, through bias control resistor 20, to the base of transistor 17. Hence, transistor 17 is direct current driven. The negative terminal of supply 18 is connected to the emitter 50 of transistor 15 and, through bias resistor 21, to the base of transistor 15. The collector of this transistor 15 is connected, through variable resistor 16, to the emitter of transistor 17. If desired, this variable resistor may be connected between primary 19 and the collector of transistor 17 to provide more amplitude on the output voltage. Diode 22 is connected between the emitter and base 55 of transistor 15 to bypass negative current around the base-emitter junction. Capacitor 23 is connected between the bases of transistors 15 and 17 to improve pulse rise time. The pulse generator output appears across the secondary winding 24 of the pulse transformer.

The trigger amplifier 12 supplies a trigger pulse to a pulse trailing edge clamp circuit by means of connection 60 25 to the gate of gated diode 26. The pulse trailing edge clamp consists of the gated diode 26 connected across a tertiary winding 27 of the pulse transformer. One termi-

nal of trigger amplifier 12, the cathode of gated diode 26 and one terminal of tertiary winding 27 are all connected to a common ground.

In operation, clock generator 10 supplies square shaped pulses to both driver amplifier 11 and trigger amplifier 12. The basic function of driver amplifier 11 is to provide sufficient power gain to produce a low voltage, high current square wave pulse to enable hard driving of the transistor switching circuit and to present a low source impedance to its input. The basic function of trigger amplifier 12 is to produce a trigger pulse of sufficient energy to trigger gated diode 26 at the trailing edge of the pulse from clock 10.

When the transistor switching circuit is in "off" condition, transistor 17 is biased by leakage current flow from emitter to collector to maintain stability. The collector of transistor 17 is at the positive potential of supply 13. The emitter of transistor 17 and the collector of transistor 15 are at approximately zero potential and the emitter of transistor 15 is at the minus potential of supply 18. Hence, the total direct current supply voltage appears across the transistor chain and yet the breakdown voltage of each transistor is not exceeded.

In order to obtain an output pulse across secondary winding 24 of the output transformer, the relatively high current square wave from driver amplifier 11 is applied to the base of transistor 15 with a resultant fast "turn-on." This causes forward biasing of transistor 17 so that ground potential is effectively applied to the terminal of primary winding 19 connected to the collector of transistor 17. With the circuit in this "on" condition, the collector of transistor 15 is at the minus potential of supply 18 less the voltage drop across its collector-emitter junction and the collector of transistor 17 is at the minus potential of supply 18 less the voltage drops across transistors 15 and 17 and variable resistor 16. Consequently, the total series voltage supplies 13 and 18 less the voltage drops across the transistors and the variable resistor is applied across primary winding 19. Of course, the output voltage level may be adjusted by variable resistor 16. After pulse occurrence, the base of transistor 15 is returned to the reverse bias condition and transistors 15 and 17 turn off. An important feature of the circuit is that the only relation of the output to the input of the transistor combination is a switching function.

By way of example the following circuit parameters may be used in the embodiment of the transistor switch shown in the drawing:

Input signal	16 volts at 91 ohm level.
Direct current supply 13	150 volts.
Direct current supply 18	150 volts.
Resistor 20	330 ohms, 1 watt.
Resistor 21	100 ohms, $\frac{1}{2}$ watt.
Variable resistor 16	200 ohms, 10 watts.
Capacitor 14	1 microfarad, 200 v. D.C.
Capacitor 23	1,000 micromicrofarads.
Diode 22	1N649 type.
Transistor 15	2N424 type.
Transistor 17	2N424 type.

A circuit constructed with these suggested components has produced output pulses of almost 300 volts and 1.2 amps. across the primary winding 19 of the output pulse transformer. Hard driving enabled obtaining rise times of less than 0.5 microsecond. The circuit has operated with a p.r.f. of firing up to 20 kc. and duration limited only by the dissipation rating of the transistors. The output impedance was 24 ohms across the primary winding 19 of the transformer plus the series impedance of variable resistor 16.

An input square wave signal with a width in the microsecond range and a rise time of 0.1 microsecond was used. Voltage levels with respect to ground during the "off" state were approximately 0 at the collector of transistor 15 and +150 v. at the collector of transistor 17.

Voltage levels with respect to ground during "on" state were -145 v. at the collector of transistor 15 and -140 v. at the collector of transistor 17 with variable resistor 16 set at zero.

Normally, the output pulse from a transistor switch would exhibit a delay in fall time due to storage effects of the transistors resulting from hard driving to obtain fast rise times. To control this fall time and also to assure a low output impedance from the pulse generator during pulse fall time and immediately following pulse occurrence, a pulse trailing edge clamp circuit is used.

A trigger pulse from the trigger amplifier 12 is applied to the gate of gated diode 26 to actuate this clamping circuit. This input trigger may be derived from the differentiated trailing edge of the square wave clock pulse, thereby coinciding with the trailing edge of the transistor switch "on" pulse. Thus, when the transistor 15 base signal goes to the "off" state, the diode 26 fires as a result of the trigger pulse applied through connection 25. As soon as the diode 26 is fired to conduct, the normally open-ended tertiary winding 27 of the transformer to which the transistor switch is connected is shunted by less than one ohm impedance, thereby producing an effective short circuit. Hence, any storage effects in the transistor switch due to hard driving are quickly clamped out and the pulse transformer output impedance is reduced to approximately zero. Diode 26 continues to conduct and the transformer output remains at close to zero impedance until all energy sources are essentially either removed or depleted. As a result, the fall time of the pulse across secondary winding 24 is determined by trigger location and the output impedance is at approximately zero during fall time and immediately following pulse occurrence.

In the illustrative embodiment of the invention under description, a ZJ39-200 type was used for gated diode 26 and high speed "tail biting" action was achieved.

To summarize, high speed square wave output pulses of high voltage and current and low source impedance are obtained from a pulse generator using a unique transistor switching circuit and pulse trailing edge clamp. The transistor switch includes a pair of series connected transistors, corresponding direct current supplies, and an output transformer. During "off" time the total supply voltage lies across the transistor chain so that the breakdown voltage of an individual transistor is not exceeded. The pulse trailing edge clamp comprises a gated diode connected across a tertiary winding on the transformer to which the transistor switch is connected. The diode is arranged to be rendered conducting in coincidence with the trailing edge of the "on" pulse applied to the transistor switch, effective to generate a short circuit across the transformer to produce short fall times and lower the source of impedance during fall time and immediately following pulse occurrence. As a result, overdrive of the transistor switch to obtain faster rise times is permissible.

Although the transistor switch has been described and illustrated as using NPN type transistors, the circuit may be modified, by reversing the supply connections, to use transistors of the PNP type. Moreover the invention is not limited to the specific illustrative embodiment shown and described but includes the full scope of the following claims.

What is claimed is:

1. An electronic pulse generator comprising: a pulse output transformer having first, second and third windings; means for applying substantially square shaped pulses of electrical energy to said first winding; and, means for providing an effective short circuit across said second winding during time periods commencing with the beginning of the fall time of said pulses applied to said first winding.
2. An electronic pulse generator comprising: an output pulse transformer having a secondary winding and first and second primary windings; a source of first sub-

stantially square wave pulses; a source of electrical energy means for applying said energy in second pulses to said first primary winding; means for providing third pulses having a leading edge coinciding in time substantially with the trailing edge of said second pulses; and, means controlled by said third pulses for providing an effective short circuit across said second primary winding.

3. A pulse generator comprising: an output pulse transformer having a secondary and first and second primary windings; a source of substantially square wave trigger pulses; a source of electrical energy and a transistor switch in series connection with each other and with said first primary winding; a gated diode connected across said second primary winding; means controlled by said trigger pulses for operating said transistor switch to cause said energy to be conducted through said first primary winding in pulses coinciding in time substantially with said trigger pulses; and, means controlled by the trailing edge of said trigger pulses for gating said diode to provide an effective short circuit across said second primary winding.

4. In a pulse circuit including a source of pulses connected to the primary of a transformer having primary, secondary and tertiary windings: a gated diode connected to a tertiary winding on said transformer; and, means for rendering said diode conductive in coincidence with any specified point in time during the duration of the pulse from said source to shape the trailing edge of the output pulse from said circuit and to lower source impedance during fall time and immediately following the occurrence of said output pulse.

5. In a pulse circuit including a source of pulses connected to the primary of a transformer having a tertiary winding: a gated diode connected to said tertiary winding on said transformer; and, means for rendering said diode conductive in coincidence with the trailing edge of the pulse from said source to produce short fall times in the output pulse from said circuit and to lower source impedance during fall time and immediately following the occurrence of said output pulse.

6. In a pulse circuit including a source of pulses connected through an amplifier to an electronic switch connected across the primary of a transformer and a means for deriving a trigger pulse from the differentiated trailing edge of the pulse from said source: a tertiary winding on said transformer; a gated diode connected across said tertiary winding; and, means for applying said trigger pulse to the gate of said gated diode to shunt said tertiary winding thereby dissipating energy in said transformer in coincidence with the trailing edge of the pulse from said source.

7. Apparatus in accordance with claim 6 wherein said electronic switch is transistorized and said gated diode when triggered into conduction is effective to clamp out storage effects due to hard driving of the transistors in said transistorized electronic switch.
